UNITED STATES PATENT OFFICE.

PAUL ARTHUR, OF CHICAGO, ILLINOIS, ASSIGNOR TO LYON & HEALY, INC., OF CHICAGO, ILLINOIS, A CORPORATION OF ILLINOIS.

DESIGN FOR A BANJO.

Application filed May 16, 1927. Serial No. 21,996. Term of patent 14 years.

To all whom it may concern:

Be it known, that I, PAUL ARTHUR, a citizen of the United States, residing at Chicago, in the county of Cook and State of Illinois, have invented a new, original, and ornamental Design for Banjos, of which the following is a specification, reference being had to the accompanying drawing, forming a part thereof.

I claim:

The ornamental design for a banjo, substantially as shown.

PAUL ARTHUR.
